(57) **CLAIM**

We claim the ornamental design for a case for a tablet shaped device with a hinge, as shown and described.

DESCRIPTION

FIG. 1 is a front perspective view of my invention a case for a tablet shaped device with a hinge in an open position; FIG. 2 is an enlarged view thereof, taken from the market labeled “2” on FIG. 1;

FIG. 3 is a further enlarged view thereof, taken from the marker labeled “3” on FIG. 1;

FIG. 4 is a back perspective view thereof, in a closed position;

FIG. 5 is an enlarged view thereof of FIG. 4 taken from the marker labeled “5” on FIG. 4;

FIG. 6 is a further enlarged view of FIG. 4 taken from the marker labeled “6” on FIG. 4;

FIG. 7 is front elevation view thereof, in a closed position;

FIG. 8 is a back elevational view thereof, in a closed position;

FIG. 9 is a top plan view thereof, in a closed position;

FIG. 10 is a bottom plan view thereof, in a closed position;

FIG. 11 is a side elevational view thereof, in a closed position; and,

FIG. 12 is a side elevational view thereof, from the side opposite that of FIG. 11.

The broken lines depict portions of the case for a tablet shaped device with a hinge that forms no part of the claim.

1 Claim, 8 Drawing Sheets
